KNIFE ADJUSTER FOR CIGARETTE
MACHINE CUT-OFFSWilhelm B. Bronander, Montclair, N. J., assignor
to American Machine & Foundry Company, a
corporation of New Jersey

Application April 19, 1933, Serial No. 666,904

8 Claims. (Cl. 131—37)

This invention relates to an improved cutoff for continuous rod cigarette machines, its main object being to provide means for adjusting the knife blade while the cutoff is in motion, thus eliminating the necessity of stopping the machine, and saving considerable time during its daily operation. This is achieved by attaching the knife blade to a slideable guide plate engaging with a screw gear shaft which is actuated by a slideable rack rod operated by means of a stationary hand wheel, the shank of which engages with a bearing of said slideable rod. Another object of this invention is to sharpen the knife to maintain a predetermined curve on its cutting edge, because it has been found that a curve having a minimum overlap over the ledger plate gives best results. The latter is achieved by employing a stationary grinder which will grind the same curve to the cutting edge of the knife at all times, thus assuring a clean and straight cut of the cigarette rod. With these and other objects not specifically mentioned in view, the invention consists in certain constructions and combinations hereinafter fully described and then specifically set forth in the claims hereunto appended.

In the accompanying drawings which form a part of this specification and in which like characters of reference indicate the same or like parts:

Fig. 1 is a sectional side elevation of a cigarette cutoff provided with the improved knife adjuster;

Fig. 2 is a sectional plan view of the knife adjuster mechanism, the cutoff disk being shown with the knife in the upmost position;

Fig. 3 is a front elevation of the cutoff disk and the attached knife blade;

Fig. 4 is a bottom view of the same as seen from line 4—4 of Fig. 3;

Fig. 5 is a plan view of the cutoff disk taken on line 5—5 of Fig. 3; and

Fig. 6 is a front elevation of the cutoff housing with the attached regulating mechanism for the knife adjuster, taken on line 6—6 of Fig. 1.

In carrying the invention into effect there is provided a rotatably mounted carrier, a wafer knife slidably mounted on said carrier, manually operable means for adjusting said knife radially outward of the carrier while the latter is rotating to compensate for wearing of the knife, and a device for incapacitating said means when the knife is worn to the end. In the best forms of construction contemplated there is also provided a stationary cylindrical grinder having its axis disposed in a plane passing through the axis of said carrier, and arranged so that one of its end

faces tangentially engages the cutting edge of said knife, whereby said knife may be adjusted outwardly while travelling to keep its cutting edge in tangential relation to said grinder and thereby grind said edge. These various means and parts may be widely varied in construction within the scope of the claims, for the particular device selected to illustrate the invention is but one of many possible concrete embodiments of the same. The invention, therefore, is not to be restricted to the specific construction shown and described.

The improved cigarette cutoff consists of a cutoff disk or carrier 10 which by means of bolts 11 is secured to flange 12 of cutoff shaft 13 continuously driven from the main drive of the cigarette machine. Carrier 10 supports, by means of a detachable bearing 14, the knife adjusting shaft 15 which is equipped with a screw or spiral gear 16 meshing with the transverse grooves of knife guide and supporting plate 17 to which is attached the knife blade 18 of the wafer type. Plate 17 and knife 18 are slidably supported in a guide plate 19 secured to the carrier by screws as shown in Figs. 3 and 4. Shaft 15, furthermore, is provided with gear teeth 20 through which it is actuated by the rack teeth 21 of rod 22 slidably supported by a guide bushing 23 mounted in the center of carrier 10. The sliding movement of rod 22 is controlled by a guide bearing 24 loosely mounted on a shank 25 of hand wheel 26, the threaded end 27 of shank 25 being supported by a threaded bearing lug 28 attached to the stationary cutoff housing 29. In order to adjust knife blade 18 while the carrier 10 is in motion, it is only required to turn hand wheel 26 in a clockwise direction in Fig. 6, which, due to the threaded mounting of shank 25, will cause the latter to move outwardly thereby effecting a similar movement of rod 22 which, through its bearing 24 is connected to shank 25.

The movement of rod 22, the rack teeth 21 of which mesh with teeth 20 of shaft 15, will cause the latter to turn, thereby also turning screw gear 16 and causing the knife guide plate 17 and knife 18 to move outwardly to the desired position, and thereby compensate for wearing of the knife. Guide bearing 24 is equipped with a sleeve 30 carrying a stop lug 31 for the purpose of preventing the disengagement of guide plate 17 from spiral gear 16 when the knife blade is worn down to the end, as in said position lug 31 engages with a stop pin 32. The machine then has to be stopped since a new knife blade is required. Stop pin 32 is of the spring plug type equipped with compression spring 33 and sup-

ported in lug 34 of stationary housing 29. In order to insert a new knife blade 18, stop pin 32 is pulled out of the way of stop lug 31 and hand wheel 26 is turned to move the rod 22 outwardly, the stop pin 32 upon its release riding on lug 31 until it drops off lug 31. At this point, guide plate 17 and knife blade 18 can easily be removed and a new blade 18 attached to plate 17 after which the latter is inserted again and the operation of stop pin 32 and hand wheel 26 is reversed until bearing 24 has reached its innermost position.

The stationary grinder (Fig. 1) consists of cylindrical grinder 35 loosely mounted on a downwardly inclined stud 36 fixed in an arm 37 attached to the side wall of housing 29. The grinder is supported in this manner, with its axis in a vertical plane passing through the axis of the cutoff disk 10, to tangentially engage and grind the cutting edge of the knife to a predetermined curve and bevel it as it moves over the outer end face of the grinder. Since the grinder is stationary, the cutting edge will always be ground to the same curvature, whereby its overlap over the ledger plate may be kept down to a predetermined minimum which is just sufficient to sever the cigarette rod, and which has been found to produce more perfect cuts through the cigarette rod.

When the operator initially adjusts the knife to engage the grinder on the ledger tube the desired overlap of the cutting edge is obtained. Whenever the operator notices that the grinder is no longer grinding the cutting edge of the knife, the operator adjusts the knife outwardly to reengage the grinder without stopping the machine, thereby keeping it in the position in which it severs the cigarette rod most efficiently.

What is claimed is:

40 1. In a cigarette cutoff, the combination with a rotatably mounted carrier, of a rod slidably mounted in said carrier and coaxial therewith, a knife adjusting shaft rotatably mounted in said carrier and extending diametrically thereof, said 45 rod having rack teeth thereon and said shaft being provided with gear teeth meshing with the rack teeth of said rod, a wafer knife, a transversely grooved guide plate carrying said knife and slidably mounted on said carrier and radially 50 adjustable thereof, and a screw gear on said shaft meshing with said grooves, whereby said rod may be moved axially outward to adjust said knife radially outward of the carrier and thereby 55 compensate for wearing of the knife while the carrier is rotating.

2. In a cigarette cutoff, the combination with a rotatably mounted carrier, of a rod slidably mounted in said carrier and coaxial therewith, a knife adjusting shaft rotatably mounted in said carrier and extending diametrically thereof, said rod having rack teeth thereon and said shaft being provided with gear teeth meshing with the rack teeth of said rod, a wafer knife, a transversely grooved guide plate carrying said knife and slidably mounted on said carrier and radially 65 adjustable thereof, a screw gear on said shaft meshing with said grooves, whereby said rod may be moved axially outward to adjust said knife radially outward of the carrier and thereby 70 compensate for wearing of the knife while the carrier is rotating, manually operable means for moving said rod outwardly to adjust the knife, and a device for obstructing the outward movement of said rod when the knife is worn to the end.

75 3. In a cigarette machine cutoff, the combina-

tion with a rotatably mounted carrier, of a rod slidably mounted in said carrier and coaxial therewith, a knife adjusting shaft rotatably mounted in said carrier and extending diametrically thereof, said rod having rack teeth thereon and said shaft being provided with gear teeth meshing with the rack teeth of said rod, a wafer knife, a transversely grooved guide plate carrying said knife and slidably mounted on said carrier and radially adjustable thereof, a screw gear on said shaft meshing with said grooves, whereby said rod may be moved axially outward to adjust said knife radially outward of the carrier and thereby compensate for wearing of the knife while the carrier is rotating, manually operable means for moving said rod outwardly to adjust the knife, and a device for obstructing the outward movement of said rod when the knife is worn to the end, said device including a lug connected to said rod, and a stationary stop pin disposed in the path of said lug.

4. In a cigarette cutoff, the combination with a rotatably mounted carrier, of a wafer knife slidably mounted on said carrier, manually operable means for adjusting said knife radially outward of the carrier while the latter is rotating to compensate for wearing of the knife, and a device for incapacitating said means when the knife is worn to the end, said means including a rod slidably mounted in said carrier and coaxial therewith, and connections between said rod and knife for moving the knife radially outward of the carrier when the rod is moved axially, and said device including a stop-pin disposed to obstruct the axial movement of said rod when the knife is worn down to the end.

5. In a cigarette cutoff, the combination with a rotatably mounted carrier, of a flat wafer knife slidably mounted on said carrier and having a curved cutting edge which is eccentric to the axis of rotation of said carrier, manually operable means for adjusting said knife radially outward of the carrier while the latter is rotating to compensate for wearing of the knife, a device for incapacitating said means when the knife is worn to the end, and a stationary cylindrical grinder having its axis disposed in a plane passing through the axis of said carrier, and arranged so that one of its end faces tangentially engages the cutting edge of said knife, whereby said knife may be adjusted outwardly while travelling to keep its cutting edge in tangential relation to said grinder and thereby grind said edge.

6. In a cigarette cutoff, the combination with a rotatably mounted knife carrier, of knife supporting means mounted on said carrier for movement diametrically thereof, means for mounting a cutoff knife on said supporting means, a manually operable element relatively stationary with respect to said carrier, a rack extending axially of said carrier and rotatable therewith, gear means meshing with said rack and connected to said knife support to move the same on movement of the rack and connections between said manually operable element and said rack to move said rack in response to actuation of said element.

7. In a cigarette cutoff, the combination with a rotatably mounted knife carrier, of knife supporting means mounted on said carrier for movement diametrically thereof, means for mounting a cutoff knife on said supporting means, a manually operable element relatively stationary with respect to said carrier, a rack extending axially of said carrier and rotatable therewith, gear means meshing with said rack and connected to said

knife support to move the same on movement of the rack and connections between said manually operable element and said rack to move said rack in response to actuation of said element, said connections including a bearing permitting free rotation of said rack relative to said element.

8. In a cigarette cutoff, the combination with a 5 rotatably mounted knife carrier, of knife supporting means mounted on said carrier for movement diametrically thereof, means for mounting a cutoff knife on said supporting means, a manually operable element relatively stationary with respect to said carrier, an actuating bar extending

axially of said carrier and rotatable therewith, means engaging with said bar and connected to said knife support to move the same on movement of the bar and connections between said manually operable element and said bar to move said bar in response to actuation of said element, said element having rotatable threaded portion, and a stationary threaded part in which said threaded portion engages for producing a fine adjustment of said element and the bar connected thereto. 10
